UNITED STATES PATENT OFFICE.

FRANCIS J. McMURDIE, OF KALAMAZOO, MICHIGAN.

FAN-BLOWER.

1,175,162.

Specification of Letters Patent. Patented Mar. 14, 1916.

Application filed April 20, 1914. Serial No. 833,096.

To all whom it may concern:

Be it known that I, FRANCIS J. McMURDIE, a citizen of the United States, residing at Kalamazoo, in the county of Kalamazoo and State of Michigan, have invented certain new and useful Improvements in Fan-Blowers, of which the following is a specification.

This invention relates to improvements in fan blowers.

The object of this invention is to provide in a blower of this type a fan wheel or rotor which is built up of units so that the size of the wheel or rotor may be readily increased or lessened as circumstances may require, and which affords a very strong and rigid construction.

Further objects, and objects relating to details and economies of structure and operation will definitely appear from the detailed description to follow.

I accomplish the objects of my invention by the devices and means described in the following specification.

25 The invention is clearly defined and pointed out in the claims.

A structure constituting a preferred embodiment of my invention is clearly illustrated in the accompanying drawing forming 30 ing a part of this specification, in which:

Figure I is a front elevation of a fan and casing embodying my invention. Fig. II is a view in side elevation of the fan shown in Fig. I. Fig. III is a sectional view taken 35 through the fan wheel on the line 3—3 of Figs. I and IV, the casing being omitted and a portion of the fan wheel being broken away for convenience in illustration. Fig. IV is a transverse sectional view taken 40 through the fan wheel on the line 4—4 of Fig. III. Fig. V is a detail enlarged perspective view of one of the curved buckets. Fig. VI is an enlarged detail sectional view on the line 6—6 of Fig. IV, showing the 45 means for supporting in spaced relation the bucket carrying rings. Fig. VII is a detail sectional view similar to Fig. III, showing by dotted lines one of the buckets secured in place at different angles relative to the ring.

50 Fig. VIII is a view in side elevation of a modified form of wheel. Fig. IX is an enlarged sectional view on the line 9—9 of Fig. VIII. Fig. X is a fragmentary sectional view of a modification showing the

buckets secured to the inner and outer faces 55 of the rings in line with each other.

In the drawing similar reference characters refer to similar parts throughout the several views, and the sectional views are taken looking in the direction of the little 60 arrows at the ends of the section lines.

Considering the numbered parts of the drawing, 1 is the base or standard carrying the casing or housing 2. The housing 2 is provided at one side with an inlet cone 3 65 which is funnel shaped and leads toward the intake opening in the side of the housing. The housing is also provided with the outlet opening 4. A shaft 6 is journaled in suitable bearings on the base or standard 1 70 and said shaft 6 carries a driving pulley 5 by means of which the shaft is revolved. Said shaft 6 extends through a suitable bearing in the side of the housing 2 into the interior thereof and a suitable hub 7 is se- 75 cured upon the end of the shaft 6 so as to rotate therewith.

8 is a solid disk or back plate which is secured to the hub 7. The fan wheel is provided with a plurality of rings 9, 10, 11, 80 12 and 13 which are supported from the back plate 8, in spaced relation thereto, by means of a plurality of bolts 13' extending through the back plate 8 and the several rings and spacing sleeves 14 which space 85 the said rings and the back plate from each other, as is clearly shown in Fig. IV. These rings are all of the same diameter and of the same diameter as the back plate 8, but the diameter of the openings in the center 90 of these rings is greater as the rings are disposed toward the front or intake end of the wheel, that is, the ring 9 which is toward the back of the wheel has a smaller central opening than the ring 10, and the ring 10 has a 95 smaller central opening than the ring 11, and so on, passing from the back end of the wheel toward the intake end thereof. Each of the rings 9, 10, 11 and 12 is provided with a deflecting flange 9', 10', 11' and 12' which 100 is curved toward the intake end of the wheel and assists in deflecting the entering stream of air toward the discharge ports of the wheel. The outer ring 13 is not provided with a flange of this type inasmuch 105 as this ring serves merely as a support for the outer row of buckets. To each of these rings and to the inner surface of the back

plate 8 are secured a plurality of curved buckets 15, which buckets are provided on one edge with an attaching flange 16, the buckets being secured in place by rivets 5 passing through said flange. Buckets are secured on both surfaces of the intermediate rings 9, 10, 11 and 12 but these buckets are staggered with relation to each other, that is, no two of the buckets secured to the inner 10 and outer surfaces of the rings are secured in line with each other. The rings are assembled in such relation to each other that the buckets carried by each ring are disposed between the buckets carried by adjacent rings, as is clearly shown in Fig. III. In each case there is a short space or gap between the free edges of the buckets opposite the attaching flanges and the next adjacent ring.

20 In Fig. X I have shown a modified arrangement of the buckets in which they are secured to the inner and outer faces of the rings in line with each other. In shape the buckets are curved, as shown in Fig. V, that 25 portion of the bucket which is disposed toward the intake chamber being curved on a shorter radius than that portion which is disposed toward the outer or discharge end of the bucket. The particular curvature of 30 the buckets may be varied without departing from the spirit of my invention. The angle at which the buckets are secured in place relative to the rings depends upon the use to which the fan is to be put. For some 35 purposes it is desirable to secure the buckets in place with the outer edge thereof in advance of the inner edge in the direction of rotation, as shown in Fig. III. For other purposes it is desirable to secure the buckets 40 in place with the lower edge in advance of the upper edge. The angle at which the buckets are secured in place forms no part of my invention, the same being adapted to be changed according to the purposes for 45 which the fan is to be used. In Fig. VII one of the buckets is shown by dotted lines secured at different angles relative to the supporting rings.

50 In Figs. VIII and IX I have shown a modified form of my invention in which I have provided spiders 18 which are fixed upon the shaft 6 to rotate therewith and upon the arms of which a plurality of rings are supported by means of bolts 13' and 55 spacing sleeves 14 in substantially the same way as in the preferred form of my invention. This modification differs from the preferred form in that the rings 19 are all alike instead of some of the rings being extended inwardly into the intake chamber and provided with curved deflecting flanges.

From the description of the parts given above, the operation of my device should be very readily understood. The fan wheel is 60 rotated by means of power applied to the

driving pulley 5 and by means of such rotation the air is drawn in between the inner edges of the bucket 15 and discharged between the outer edges thereof. This draws the air out of the intake chamber, which 70 comprises the space within the wheel or drum, and air is drawn through the inlet 75 cone 3 into the intake chamber. The air entering thus is deflected upwardly to the ports between the buckets by means of the 80 deflecting flanges 9', 10', 11' and 12' on the rings 9, 10, 11 and 12. The distance to which the rings extend toward the center 85 of the wheel is proportional to the distance at which said rings are located from the intake end of the wheel so that a proper proportion of the air is deflected toward each 90 group of ports to be discharged therefrom.

In Fig. VIII I have shown a modification which differs from my preferred form in 95 that there are no deflecting flanges provided upon the rings and these rings are substantially alike, the air being drawn in to the intake chamber and discharged between the outer edges of the buckets. It will be seen 90 that this wheel can readily be increased or diminished in size by removing the outer ring, such as ring 13 in Fig. IV, and adding or removing the required number of intermediate rings with the buckets carried thereby. In this way it will be seen that I have provided a unit wheel which is built up in 95 units, the wheel being built up and assembled to the dimensions required according to the use to which it is to be devoted.

I am aware that the particular structure which I have here shown is susceptible of considerable variation without departing from the spirit of my invention and, hence, I do not wish to be restricted to the same. 105 I have found, however, that this form is to be preferred, and, therefore, I desire to claim the same specifically as well as broadly as indicated by my appended claims.

Having thus described my invention, what 110 I claim as new and desire to secure by Letters Patent is:—

1. In a structure of the class described, the combination with a shaft, of a drum 115 mounted thereon to rotate therewith, said drum comprising a back plate secured to said shaft, a plurality of rings carried by said back plate in spaced relation thereto, said back plate and said rings being of the same external diameter, the central openings 120 of said rings varying in diameter in proportion to the distance from the back plate, deflecting flanges provided on the intermediate rings at the inner edges thereof, said flanges being curved toward the intake end 125 of said drum, and curved buckets carried by said rings at the periphery thereof, said buckets being disposed in staggered relation to each other, and said rings being secured together so that each bucket is disposed be- 130

5 tween buckets carried by adjacent rings, there being a space between each of said buckets and the adjacent ring, and each of said buckets being provided with an attaching flange at one edge for securing said bucket to the supporting ring, all coacting substantially as described for the purpose specified.

10 2. In a structure of the class described, the combination with a shaft, of a drum mounted thereon to rotate therewith, said drum comprising a back plate secured to said shaft, a plurality of rings carried by said back plate in spaced relation thereto, 15 said back plate and said rings being of the same external diameter, the central openings of said rings varying in diameter in proportion to the distance from the back plate, deflecting flanges provided on the intermediate rings at the inner edge thereof, said flanges being curved toward the intake end of said drum, and curved buckets carried by said rings at the periphery thereof, said buckets being disposed in staggered relation to each other, and said rings being secured together so that each bucket is disposed between buckets carried by adjacent rings, there being a space between each of said buckets and the adjacent ring, all coacting substantially as described for the purpose specified.

20 3. In a structure of the class described, the combination with a shaft, of a drum mounted thereon to rotate therewith, said drum comprising a back plate secured to said shaft, a plurality of rings carried by said back plate in spaced relation thereto, said back plate and said rings being of the same external diameter, the central openings of said rings varying in diameter in proportion to the distance from the back plate, deflecting flanges provided on the intermediate rings at the inner edge thereof, said flanges being curved toward the intake end of said drum, and curved buckets carried by said rings at the periphery thereof, and said rings being secured together so that each bucket is disposed between buckets carried by adjacent rings, there being a space between each of said buckets and the adjacent ring, all coacting substantially as described for the purpose specified.

25 4. In a structure of the class described, the combination with a shaft, of a drum mounted thereon to rotate therewith, said drum comprising a back plate secured to said shaft, a plurality of rings carried by said back plate in spaced relation thereto, said back plate and said rings being of the same external diameter, the central openings of said rings varying in diameter in proportion to the distance from the back plate, and curved buckets carried by said rings at the periphery thereof, and said rings being secured together so that each bucket is dis-

posed between buckets carried by adjacent rings, there being a space between each of said buckets and the adjacent ring, all coacting substantially as described for the purpose specified.

5. In a structure of the class described, the combination with a shaft, of a drum mounted thereon to rotate therewith, said drum comprising a back plate secured to said shaft, a plurality of rings carried by said back plate in spaced relation thereto, the central openings of said rings varying in diameter in proportion to the distance from the back plate, and said rings being secured together so that each bucket is disposed between buckets carried by adjacent rings, there being a space between each of said buckets and the adjacent ring, all coacting substantially as described for the purpose specified.

10 6. In a structure of the class described, the combination with a shaft, of a drum mounted thereon to rotate therewith, said drum comprising a back plate secured to said shaft, a plurality of rings carried by said back plate in spaced relation thereto, and curved buckets carried by said rings at the periphery thereof, and said rings being secured together so that each bucket is disposed between buckets carried by adjacent rings, there being a space between each of said buckets and the adjacent ring, all coacting substantially as described for the purpose specified.

15 7. In a structure of the class described, the combination with a shaft, of a drum mounted thereon to rotate therewith, said drum comprising a back plate secured to said shaft, a plurality of rings carried by said back plate in spaced relation thereto, and curved buckets carried by said rings at the periphery thereof, and said rings being secured together so that each bucket is disposed between buckets carried by adjacent rings, all coacting substantially as described for the purpose specified.

20 8. In a structure of the class described, the combination with a shaft, of a drum mounted thereon to rotate therewith, said drum comprising a back plate secured to said shaft, a plurality of rings carried by said back plate in spaced relation thereto, and curved buckets carried by said rings at the periphery thereof there being a space between each of said buckets and the adjacent ring, all coacting substantially as described for the purpose specified.

25 9. In a structure of the class described, the combination with a shaft, of a drum carried thereby, and comprising a back plate mounted on said shaft, a plurality of bolts carried by said back plate, a plurality of rings carried by said bolts, spacing sleeves on said bolts supporting said rings in spaced relation to each other and to said back plate,

and a plurality of curved buckets carried by said rings there being a space between each of said buckets and the adjacent ring, all coacting substantially as described for the purpose specified.

5 10. In a structure of the class described, the combination with a shaft, of a drum comprising a plurality of rings carried by said shaft, bolts passing through said rings, 10 spacing sleeves mounted on said bolts and supporting said rings in spaced relation to each other, and curved buckets carried by said rings there being a space between each of said buckets and the adjacent ring, all coacting substantially as described for the purpose specified.

15 20. In a structure of the class described, the combination with a shaft, of a drum comprising a plurality of rings carried by said shaft and supported in spaced relation to each other, a plurality of curved buckets carried by each of said rings at its periphery, said buckets being disposed in staggered relation to each other, and being provided 25 at one edge with an attaching flange by means of which it is attached to the supporting ring, the edge of said bucket opposite said flange being spaced from the adjacent ring, all coacting substantially as described 30 for the purpose specified.

35 40. In a structure of the class described, the combination with a shaft, of a drum comprising a plurality of rings carried by said shaft and supported in spaced relation to each other, a plurality of curved buckets carried by each of said rings at its periphery, said buckets being provided at one edge with an attaching flange by means of which it is attached to the supporting ring, the edge of said bucket opposite said flange being spaced from the adjacent ring, all coacting substantially as described for the purpose specified.

45 50. In a structure of the class described, the combination with a shaft, of a drum comprising a plurality of rings carried by said shaft so as to rotate therewith, a plurality of curved buckets carried by each of said rings at the periphery thereof, each of said buckets being attached to said rings at one edge and having the opposite edge free, all coacting substantially as described for the purpose described.

55 60. In a structure of the class described, the combination with a shaft, of a drum mounted to rotate therewith, said drum comprising a plurality of rings carried by said shaft in spaced relation to each other, said rings being of the same external diameter, the central openings of said rings varying in diameter in proportion to the distance from the intake end of said drum, deflecting flanges curved toward the intake end of said drum provided at the inner edges of 65 said rings, and curved buckets carried by

said rings at the periphery thereof, said buckets being disposed in staggered relation to each other and said rings being secured together so that each bucket is disposed between buckets carried by adjacent rings 70 there being a space between each of said buckets and the adjacent ring and each of said buckets being provided with an attaching flange at one edge for securing said bucket to the supporting ring, all coacting substantially as described for the purpose specified.

75 80. In a structure of the class described, the combination with a shaft, of a drum mounted to rotate therewith, said drum comprising a plurality of rings carried by said shaft in spaced relation to each other, said rings being of the same external diameter, the central openings of said rings varying in diameter in proportion to the distance 85 from the intake end of said drum, deflecting flanges curved toward the intake end of said drum provided at the inner edges of said rings, and curved buckets carried by said rings at the periphery thereof, said buckets being disposed in staggered relation to each other and said rings being secured together so that each bucket is disposed between buckets carried by adjacent rings 90 there being a space between each of said buckets and the adjacent ring, all coacting substantially as described for the purpose specified.

95 100. In a structure of the class described, the combination with a shaft, of a drum mounted to rotate therewith, said drum comprising a plurality of rings carried by said shaft in spaced relation to each other, said rings being of the same external diameter, the central openings of said rings varying in diameter in proportion to the distance 105 from the intake end of said drum, deflecting flanges curved toward the intake end of said drum provided at the inner edges of said rings and curved buckets carried by 110 said rings at the periphery thereof and said rings being secured together so that each bucket is disposed between buckets carried by adjacent rings there being a space between each of said buckets and the adjacent 115 ring, all coacting substantially as described for the purpose specified.

120 125. In a structure of the class described, the combination with a shaft, of a drum mounted to rotate therewith, said drum comprising a plurality of rings carried by said shaft in spaced relation to each other, said rings being of the same external diameter, the central openings of said rings varying in diameter in proportion to the distance 125 from the intake end of said drum, and said rings being secured together so that each bucket is disposed between buckets carried by adjacent rings there being a space between each of said buckets and the adj- 130

cent ring, all coacting substantially as described for the purpose specified.

18. In a structure of the class described, the combination with a shaft, of a drum 5 mounted to rotate therewith, said drum comprising a plurality of rings carried by said shaft in spaced relation to each other, the central openings of said rings varying in diameter in proportion to the distance from 10 the intake end of said drum, and curved buckets carried by said rings at the periphery thereof and said rings being secured together so that each bucket is disposed between buckets carried by adjacent rings 15 there being a space between each of said buckets and the adjacent ring, all coacting substantially as described for the purpose specified.

19. In a structure of the class described, 20 the combination with a shaft, of a drum

mounted to rotate therewith, said drum comprising a plurality of rings carried by said shaft in spaced relation to each other, the central openings of said rings varying in diameter in proportion to the distance from 25 the intake end of said drum, and curved buckets carried by said rings at the periphery thereof, and said rings being secured together so that each bucket is disposed between buckets carried by adjacent rings, all 30 coacting substantially as described for the purpose specified.

In witness whereof, I have hereunto set my hand and seal in the presence of two witnesses.

FRANCIS J. McMURDIE. [L.S.]
